UNITED STATES PATENT OFFICE.

HYMAN SOLOMON, OF NEW YORK, N. Y.

DESIGN FOR A COMBINATION BIRD CAGE AND AQUARIUM.

Application filed March 21, 1928. Serial No. 25,935. Term of patent 7 years.

To all whom it may concern:

Be it known, that I, HYMAN SOLOMON, subject of Roumania, residing at New York, in the county of New York and State of New York, have invented a new, original, and ornamental Design for a Combination Bird Cage and Aquarium, as shown in the accompanying drawing and described in the following specification.

Figure 1 is a plan view of a combination bird cage and aquarium of my approved design.

Figure 2 is a perspective view of the same.

I claim:

The ornamental design for a combination bird cage and aquarium as shown.

HYMAN SOLOMON.
